P.C.; John K. Buche; Bryce A. Johnson(57) **CLAIM**

I claim the ornamental design for an “earring,” as shown.

DESCRIPTION

FIG. 1 is a perspective view of an earring showing my new design;

FIG. 2 is front view of the earring of FIG. 1;

FIG. 3 is a back view of the earring of FIG. 1;

FIG. 4 is a left side view of the earring of FIG. 1;

FIG. 5 is a right side view of the earring of FIG. 1;

FIG. 6 is a top view of the earring of FIG. 1;

FIG. 7 is a bottom view of the earring of FIG. 1; and,

FIG. 8 is an environmental view of the earring of FIG. 1. Broken lines depict portions of the earring and environment that form no part of the claimed design.

The earring features a unique appearance over prior art, including uprights and a transparent block that shows a double image illusion when viewed at certain angles.
